CLAIM

The ornamental design for a two-shafted golf club neck, as shown and described.

DESCRIPTION

FIG. 1 is an isometric view of a two-shafted golf club neck in accordance with the invention;

FIG. 2 is a top view of the two-shafted golf club neck;

FIG. 3 is a bottom view of the two-shafted golf club neck;

FIG. 4 is a front view of the two-shafted golf club neck;

FIG. 5 is a rear view of the two-shafted golf club neck;

FIG. 6 is a side view of the two-shafted golf club neck;

FIG. 7 is a side view of the two-shafted golf club neck; and,

FIG. 8 is an isometric view of the two-shafted golf club neck, the broken line showing of the golf putter head and the fragmented shafts are for illustrative purposes only and forms no part of the claimed design.
